UNITED STATES PATENT OFFICE.

LORETTA KEIFER GOTTSCHALL AND JOHN B. AUFULDISH, OF DAYTON, OHIO; SAID AUFULDISH ASSIGNOR TO SAID GOTTSCHALL.

SIGNALING DEVICE FOR AUTOMOBILES.

1,182,268.

Specification of Letters Patent.

Patented May 9, 1916.

Application filed December 12, 1914. Serial No. 876,918.

To all whom it may concern:

Be it known that we, LORETTA KEIFER GOTTSCHALL and JOHN B. AUFULDISH, citizens of the United States, residing at Dayton, in the county of Montgomery and State of Ohio, have invented certain new and useful Improvements in Signaling Devices for Automobiles, of which the following is a specification, reference being had therein to 10 the accompanying drawing.

This invention relates to signaling devices for automobiles and similar vehicles, and is designed more particularly for giving traffic signals.

15 The object of the invention is to provide a device which can be operated from the driver's seat to signal both the traffic officer in front of the vehicle and following vehicles, to inform them of the movement 20 which the vehicle carrying the signal is about to make, that is, to indicate whether it intends to stop or to turn to the right or to turn to the left.

It is also an object of the invention to 25 produce such a signaling device which will be simple in its construction and positive in its operation, and, to this end it is a further object of the invention to provide means whereby the movement of one signal 30 into signaling position will automatically cause the then exposed signal to be moved out of signaling position, so that only one signal at a time can be exposed.

Figure 1 of the drawings is a sectional 35 vertical view taken along one side of the apparatus showing the signals and their controlling devices in elevation; Fig. 2 is a horizontal sectional view showing the signal operating devices in plan; Fig. 3 is an 40 end elevation partly broken away; and Fig. 4 is a detail view of the selective operating mechanism.

In these drawings we have illustrated one embodiment of our invention and have 45 shown the same as comprising a series of arms having signaling devices at their outer ends, after the manner of a semaphore. Each signal comprises two arms or semaphores which are rigidly connected together 50 to form a single signal. Preferably, the arms of the signaling devices are spaced

apart different distances so that they may nest, that is, they may be arranged one within the other to store them in compact arrangement when in their idle positions. 55 Each arm of each signal carries a mark, word or other indication, the indication carried by the one arm being visible from one side of the device and the indication carried by the other arm being visible from 60 the opposite side of the device. In connection with these signals, we have provided a selective operating device operable from the driver's seat for causing a selected signal to be exhibited, and the previously exhibited 65 signal to be returned to its idle position.

The signals may be mounted and operated to secure the desired results in different manners and, in the accompanying drawings, we have illustrated one mechanism 70 which is satisfactory in operation.

As here shown, the device comprises a casing 1 which constitutes a main frame on which the several parts of the apparatus are mounted. This frame may be secured 75 to any part of the vehicle which is adapted to support the same. It is especially designed, however, to be mounted on the side of a closed vehicle, such as a coupé or limousine. Mounted in the side members of 80 this casing is a shaft 2 which forms a support for the signals, which are shown at 3, 4 and 5. Each signal comprises an outer portion or signal proper in the form of a plate or, preferably, a frame in which is 85 mounted a plate of glass or the like. These plates or signals proper are carried by arms 6, and these arms are rigidly connected one to the other to connect the signals in pairs and cause them to operate in synchronism. 90 The outermost signals 3 may be connected directly to the shaft 2, while the signals 4 and 5 are connected by tubular shafts or sleeves 7 and 8, these tubular shafts being mounted one upon the other and upon the 95 shaft 2. That portion of the casing through which the signal arms extend may be open, but is preferably slotted, as shown at 9, thereby partially closing the same and providing guides for the signal arms. The 100 upper wall of the casing and the front wall of the casing form stops at the ends of the

slots which serve to limit the movements of the signals in the respective directions. The several signaling devices being so mounted that they are capable of separate movement. It will be apparent that any one of the signals may be moved into signaling position independently of the other signals. In the present arrangement of the device "signaling position" is that position in which the signals extend above the top of the casing, the signals being so arranged that the lettering thereon is readable when in that position. When the signal arms are in their horizontal positions, the signals are in their inoperative positions. They may be concealed if desired, but this is not necessary, and they are not so shown in this instance because when the signals are so arranged the lettering extends vertically and cannot be easily read and, therefore, is not effective as a signal.

The signals may be controlled to move them into and out of their operative or signaling positions by any suitable mechanism. Preferably we employ a selective operating mechanism having means to separately actuate the several signals and in the particular form of the device here shown we employ an adjustable selector which has an operable portion extending to a position remote from the signals where it may be readily actuated to cause the operation of the desired signal. It will be understood, however, that the use of a single selector adjustable to cause the operation of a selected signal is not essential to the carrying out of the invention. The operating mechanism in its main features of construction will be substantially the same whether a single adjustable selector is used or not, and will comprise an actuating device having an operable part arranged at a point remote from the signals and connecting devices, whereby the actuating device may be operatively connected with the selected one of the signals. The actuating and connecting devices may be of various kinds.

As here shown, one arm 6 of each signal is provided with a crank arm 10 which may be formed integral therewith and extends rearwardly and downwardly therefrom after the manner of a bell crank. Pivoted connected to each crank arm is a connecting device which comprises a slide bar 11 provided with a longitudinal slot 12 by means of which it is mounted on a guide pin or stud 13 which is mounted in an intermediate frame member 14 secured to the top and bottom walls of the casing and coöperating therewith to support this mechanism. Preferably, the several slide bars 11 are all mounted on the same guide pin and are of substantially the same length so that when the several signals are in their idle positions

the rear ends of the slide bars will be substantially in transverse alinement. Coöperating with each of these slide bars is an actuating device, there being, in the present instance, as above stated, a single actuating device adapted to select and operate any one of the slide bars. In the particular embodiment of the invention here illustrated the actuating device comprises two parts, one of these parts being in the form of a shaft or push rod 16 and the other in the form of a spider 15 mounted on the rod 16 and having three arms which are so arranged that each arm may be moved into engagement with a different one of the slide bars, and when one arm is in engagement with its slide bar the other arms will be out of alinement with their slide bars, thereby permitting the spider to move past these other arms without engaging the same. We have, in the present instance, employed a separate arm on the spider for each signal, as, in this manner, we can more readily avoid the interference of the arms with signals other than the one being actuated, but, it will be readily understood, that this is not an essential feature of the actuating device, as it may be of any shape which will enable it to be moved into independent engagement with the several slide bars. In the arrangement of the device here shown the shaft 16 extends through the wall in which the casing 1 is mounted and is provided on that side of the wall opposite the signals with a handle 17, by means of which it may be rotated to bring the proper arm into alinement with the slide bar of that signal which it is desired to operate. As a guide to this setting operation, the handle is caused to move over a gage or guide plate 18 which is provided with indications to indicate the proper point at which the handle should be stopped. In the present instance these indications are in the form of recesses or sockets formed in the face of the plate and adapted to receive a spring pressed pin 19 mounted in the handle and having a knurled head 20, by means of which it may be actuated. The guide plate may be lettered adjacent to each socket to indicate the signal which will be operated when the handle is adjacent to that socket.

Axial movement may be imparted to the actuating device to cause the operation of the selected signal, in any suitable manner. To this end the spider is rigidly secured to the shaft 16 so that it will rotate therewith and will move axially therewith. The handle 17 is keyed to the shaft by means of a pin projecting into a slot 21 extending lengthwise of the shaft, so that the movement of the handle will impart rotation to the shaft but the shaft may move axially independently of the handle. Preferably, the actuating device is automatically returned

to its normal position and to this end we have extended the shaft 16 beyond the spider and have mounted the inner end thereof in a bearing block 22. Around this 5 shaft is coiled a spring 23 bearing at one end against the bearing block 22 and at the other end against the face of the actuator. The bearing block 22 also cooperates with the bearing in the supporting wall to guide 10 the shaft 16 in a straight line and thus maintain the actuating device in proper alignment with the selected slide bar.

The signals may be retained in their elevated positions by any suitable mechanism. 15 In the present instance we have provided one arm of each signal with a pin 24 adapted to be engaged by a detent 25 pivoted on a stud mounted in the frame member 14 near the top of the casing. These detents have 20 beveled noses so that the pins will engage the noses and depress the detents to permit the pins to move into operative engagement therewith. The detents for the arms of the three signals are preferably mounted on a 25 single stud, as shown at 26, and may be operated by a single arm or a plurality of arms. In the present instance, however, we have shown the three detents as rigidly connected one to the other and provided with a single 30 tail piece 27 to which is connected a spring 28 which tends to hold the three detents, which constitute in effect a single detent, in their uppermost or operative position. Obviously, when any one of the signals is 35 moved upward into its signaling position, the pin carried by the arm thereof will engage the nose of one of the detents and ride over the same into operative engagement therewith and will thus be retained in its signaling position until the detent has been 40 actuated to release it. It is preferable that the detent should be automatically actuated to release that signal which is in signaling position before another signal moves into 45 signaling position. To accomplish this we have provided a trip lever 29 pivotally mounted between its ends on a stud 30 carried by the frame member 14 and having one end provided with a pin 31 arranged in 50 alinement with the tail 27 of the detent. The other end of the trip lever is provided with a pin or bar 31 extending transversely to the ends of one set of arms for the signaling devices, and is arranged to be engaged by 55 projecting portions or cams 32 secured to the respective arms near their points of connection with the crank arms 10, thus, when any one of the signals move upward the cam shaped portion 32 of its arm will engage the bar 31 of the trip lever 29, and 60 rock the same about its axis to cause the pin 31 to engage the tail 27 of the detent, thus actuating the detent and releasing any signal which may be in signaling position. A

spring 33 connected with the trip lever 65 serves to hold the same normally out of engagement with the tail of the detent. It will be understood that the cam portion 32 of the signal arm may be so arranged as to cause the trip lever to be actuated at any desired 70 time, but, preferably, this actuation takes place during the first portion of the movement of the signal. These signals may be mounted so that gravity alone will tend to move them into their inoperative positions 75 when the detents are released, but we prefer to employ a light spring to impart the initial movement to each signal when its detent is released, and, to this end, we have provided the several signal arms with crank 80 arms or projecting pins 34 to which are secured coiled springs 35, the opposite ends of which are connected with a fixed part of the frame. It will be apparent, therefore, that as one signal begins to move upward the detent will be actuated to release the signal which is in signaling position, that the spring 25 will move that signal across its center of gravity and that it will then move downward by gravity to its idle position. 85 Preferably, the edge of the casing, which forms the support for the signals when in their idle positions, is provided with a buffer such as a piece of leather 36 to cushion the downward movement of the signals and 90 reduce both the noise and the shock due to that movement.

The device being designed for night use as well as day use, it is desirable that means should be provided for illuminating the signals after dark. To this end we have mounted on the casing near the center thereof an electric lamp 37 which is so arranged that when any one of the signal devices is in signaling position the two parts thereof 100 will be arranged on opposite sides of the lamp, thereby causing both parts to be illuminated and enabling the signal to be read from the front and from the rear at night as well as in the daytime. This lamp may 105 be mounted in any suitable circuit and may be operated from any suitable source of current. In the present instance we have connected it in the lighting circuit for the automobile. A switch 41 is mounted on the 110 frame which supports the casing, by means of which the circuit as a whole may be controlled, thus enabling the circuit to be broken and the lamp prevented from being illuminated in the daytime.

The operation of the mechanism will be 115 readily understood from the foregoing description, and it will be apparent that any given group of signals may be provided to indicate any movement which the vehicle is liable to make, and that any one of these signals may be displayed at the will of the operator, and that when so displayed it will 120

be visible not only to following vehicles but also the traffic officer in front of the vehicle. It is also apparent that the device is so constructed that the signal on display will be automatically moved out of signaling position when another signal is moved to that position, thereby preventing confusion or mistakes due to the inadvertent retention of the former signal in signaling position. 10 Further, it will be apparent that the device is simple in its construction and positive in its operation, that the parts are of such a construction that they will not be easily disarranged or rendered inoperative by the vibrations of the vehicle, and that the device is of such a character that it can be very readily manipulated by the driver in his or her seat in the vehicle. Where the device is mounted on the side wall of a closed vehicle 15 the operating handle may be arranged on the inner wall where it can be easily actuated, or, if the device is used with a vehicle in which this is not convenient or practical, then the operating mechanism for the actuating device may be mounted at any suitable 20 point, and connecting devices of a well known type interposed between the same and the actuating device.

While we have shown one embodiment of 30 our invention, we wish it to be understood that this is shown for the purpose of illustration only, and we do not desire to be limited to the details of construction shown and described, for obvious modifications will occur to a person skilled in the art.

Having thus fully described our invention, what we claim as new and desire to secure by Letters Patent, is:

1. In a signaling device, a casing, a plurality of visual signals individually movable into and out of signaling position, each of said signals comprising an arm pivotally mounted in said casing and a display portion carried by said arm, a crank arm connected with said signal, a connecting device mounted in said casing for both sliding and pivotal movement and pivotally connected to said crank arm, and a push rod slidably mounted in the wall of said casing and arranged to engage and actuate said connecting device.

2. In a signaling device, a casing, a plurality of visual signals individually movable into and out of signaling position, each of said signals comprising two rigidly connected arms and a display portion carried by each arm, said display portions being arranged to be simultaneously visible from opposite directions when in signaling position and said arms being pivotally mounted in said casing, a lamp arranged to lie between the two parts of said signal when the latter is in signaling position, a connecting device slidably mounted within said casing

and operatively connected with said signal, 65 and an actuating device slidably mounted in the wall of said casing and having a part extending into said casing to engage said connecting device and having a part arranged exteriorly of said casing to form a handle 70 whereby said signal may be operated.

3. In a signaling device, a combination with a casing, a plurality of visual signals independently mounted in said casing on a common axis for movement into and out of 75 signaling position, a plurality of slide bars mounted within said casing and arranged in operative relation with the respective signals, a push rod mounted in the wall of said casing, a rotatable selective 80 member mounted on said push rod for movement into operative relation with a selected one of said slide bars, means for adjusting said selective member and for imparting longitudinal movement to said push rod and 85 said member.

4. In a signaling device, a plurality of visual signals separately movable into and out of operative position, a slide bar connected with each of said signals, an actuator having a plurality of arms adapted to be moved into operative relation with the respective slide bars, means for imparting movement to said actuator to cause one of 90 said arms to be moved into operative relation with its slide bar, and for imparting operative movement to said actuator to cause that slide bar and its signal to be operated. 95

5. In a signaling device, a plurality of visual signals, each comprising two parts, 100 connected one to the other for movement in synchronism and each part carrying the same indication, the indications of the two parts being visible from opposite directions, and the two parts of the several signals being spaced different distances apart to enable the several signals to be moved into alignment, and means for actuating a selected one of said signals.

6. In a signaling device, a plurality of 110 visual signals each comprising two parts connected one to the other for movement in synchronism, each carrying the same indication, and each having an arm, a plurality of nested shafts to the opposite ends of 115 which the two arms of the respective signals are connected, means to independently actuate said shafts to cause a selected signal to be moved into signaling position, and a lamp arranged to lie between the two parts 120 of said signal when the latter is in signaling position.

7. In a signaling device, a plurality of visual signals, each comprising two parts, connected one to the other for movement in 125 synchronism and each part carrying the same indication, the indications of the two parts being visible from opposite directions,

and the two parts of the several signals being spaced different distances apart to enable the several signals to be moved into alinement, and means to move a selected one of said signals into signaling position, and a lamp so mounted as to lie between the two parts of that signal which is in signaling position.

In testimony whereof, we affix our signatures in presence of two witnesses.
